UNITED STATES PATENT OFFICE.

TONY FRANCISCO, OF SOUTH CLE ELUM, WASHINGTON.

AIR-PROPELLER.

1,242,788.

Specification of Letters Patent.

Patented Oct. 9, 1917.

Application filed March 21, 1917. Serial No. 156,335.

To all whom it may concern:

Be it known that I, TONY FRANCISCO, a citizen of the United States, residing at South Cle Elum, in the county of Kittitas 5 and State of Washington, have invented certain new and useful Improvements in Air-Propellers; and I do hereby declare the following to be a full, clear, and exact description of the invention, such as will enable others skilled in the art to which it 10 appertains to make and use the same.

The invention relates to an air propeller for sleds, ice boats and various other purposes.

15 The object of the present invention is to provide a simple, practical and efficient air propeller of strong, durable and comparatively inexpensive construction adapted to be installed as a unit on ice boats, sleds and 20 various other devices and equipped with a plurality of adjustable propellers and provided with means for changing the angularity of the blades for controlling the speed of the sled, air ship or other device to which 25 the air propeller is applied, and capable also of enabling the propellers to operate as a brake for retarding the forward movement of the sled or ice boat when the same is descending an incline, or it is designed 30 to check the speed and stop the same.

A further object of the invention is to provide an air propeller of this character adapted to enable one or more propellers to be used and to be adjusted simultaneously 35 and also to be readily operated to rotate them in opposite directions or in the same direction.

With these and other objects in view, the invention consists in the construction and 40 novel combination of parts hereinafter fully described, illustrated in the accompanying drawings and pointed out in the claims here- to appended; it being understood that various changes in the form, proportion, size 45 and minor details of construction, within the scope of the claims, may be resorted to without departing from the spirit or sacri- ficing any of the advantages of the in- vention.

50 In the drawings:

Figure 1 is a side elevation of an air propeller constructed in accordance with this invention.

55 Fig. 2 is a horizontal sectional view of the same.

Fig. 3 is an enlarged longitudinal sec-

tional view through the front and rear propellers.

Fig. 4 is a transverse sectional view on the line 4—4 of Fig. 3. 60

Fig. 5 is a horizontal sectional view through the front portion of the mechanism.

Fig. 6 is a transverse sectional view taken substantially on the line 6—6 of Fig. 3. 65

Fig. 7 is a transverse sectional view on the line 7—7 of Fig. 1.

Fig. 8 is a similar view on the line 8—8 of Fig. 1.

Figs. 9 and 10 are detail views of the 70 lever frames.

Fig. 11 is a detail view of the operating lever.

Like numerals of reference designate 75 corresponding parts in the several figures of the drawings.

In the accompanying drawings in which is illustrated the preferred embodiment of the invention, the air propeller comprises in its construction a pair of propellers arranged one in advance of the other and designed to be simultaneously rotated in opposite directions in order to afford the rear propeller greater action on the air, but the propellers may be rotated in the same direction and only one propeller need be employed when it is not required to have the speed and power developed by a pair of propellers. The rear propeller comprises in its construction a central head or hub 90 casing 1 designed to be constructed of suitable metal and preferably made sectional, as shown, it being illustrated in the accompanying drawings as consisting of a pair of front sections 2 and a tapered rear section 3. The front sections form a rectangular body portion to the hub or head casing and each side of the rectangular portion of such casing is provided with bearing openings for the reception of propeller cranks 4 and 5 arranged in pairs, the members of each pair being disposed diametrically opposite each other and having their cranks reversely arranged and connected with a pivotally mounted lever frame 6 at opposite 100 sides of the pivots 7 thereof, which are mounted in the hub or head casing at opposite sides of the same in suitable bearing openings. The propellers may be made of any desired size and the propeller cranks 110 are provided with suitable bearings or bearing portions and are maintained against rel-

2
ative longitudinal movement and are provided with attaching portions 8 located exteriorly of the hub or head casing and secured to the inner portions of the propeller 5 blades 9, which are secured at their outer ends to caps or attaching portions 11 of journals 12, which are mounted in bearing openings of a hoop or ring 13, and suitably secured to the same so that the blades of 10 the propeller will be mounted at their inner and outer ends and will prevent breakage of the parts in event of the breaking of the propeller blades at the center or any point between their ends. The propeller blades 15 are detachably secured to the said attaching portions of the cranks and the outer journals and may be readily removed, renewed or repaired as required. The casing 14 of the front propeller is truncated at the back and 20 the front propeller is the one designed to be eliminated when it is desired to employ only a single propeller.

The lever frame 6 of the rear propeller is oblong and composed of spaced sides and 25 connecting ends 15 constituting pivots and connected by links 16 with two of the oppositely or reversely arranged cranks of the rear propeller. The journals 7, which extend from the centers of the sides of the 30 lever frame, are provided with reversely arranged cranks 17 having their terminal portions in the planes of the end pivots of the lever frame and connected by links 18 with the other set of cranks 5 of the propeller 35 blades. By this construction and arrangement the four blades of the rear propeller are adjusted simultaneously to change their angularity when the lever frame is adjusted. The lever frame of the rear propeller is connected by a link 19 with an inner centrally 40 arranged operating or shifting rod 20 and it is provided at one of its terminal portions with a transverse pivot 21 to receive the rear end of the link 19. The lever frame 45 22 of the front propeller is constructed substantially the same as the lever frame of the rear propeller with the exception that the sides of the front propeller frame are provided with spaced ears 23, which are connected by a pair of links 24 with side shifting rods 25. The inner centrally arranged shifting rod and the outer side shifting rods are simultaneously operated, by the means hereinafter described, to correspondingly 50 adjust the propeller blades and set the same at the desired angle. The propeller blades may be constructed of any suitable material and may be of any preferred form, four blades being preferably provided for each 55 of the propellers so as to reduce the speed necessary to develop a given amount of power, as a lower speed will be required than when the propeller is equipped with only two blades. A pair of blades may, 60 however, be employed as the change falls

within the purview of the present invention.

The hub casing, the propeller blades and the hoops or rings rotate as a unit and the rear hub or head casing 1 is keyed to a central longitudinal shaft 26 having a central bore or opening for the passage of the shifting rod 20 and arranged within an outer tubular shaft 27, which is keyed at its rear end to the hub or head casing 14 of the front 75 propeller. Front and rear bearings 28 and 29 are provided for the inner and outer longitudinal shafts. The front bearing 28, which is located at the front end of the inner longitudinal shaft, comprises an inner rotary bearing sleeve 30 and an outer sectional bearing box provided with interiorly arranged annular grooves 31 for the reception of correspondingly arranged annular ribs 32 formed on the exterior of the bearing sleeve 30 and interlocking the inner longitudinal shaft with the sectional bearing box whereby the inner longitudinal shaft is held against longitudinal movement and is permitted free rotary movement. The 80 bearing sleeve 30 is suitably secured to the front end of the inner longitudinal shaft and the outer sectional boxing or casing is mounted in a fixed position upon a supporting frame 33. The inner longitudinal shaft 85 is also equipped with a sprocket wheel 34 preferably of a sectional construction and mounted on the rear portion of the bearing sleeve 30, but it may be applied to the inner longitudinal shaft in any other desired manner. The rear bearing, which is constructed substantially the same as the front bearing, is composed of an outer sectional box or casing and an inner bearing sleeve 35 for the shaft 26 provided with ribs 36, which 90 fit in corresponding grooves 37 similar to the ribs and grooves of the front bearing. The outer longitudinal shaft is also equipped with a sectional sprocket wheel 38, which is preferably mounted on the shaft 27, as 95 shown, but it may be applied to the outer longitudinal shaft in any other desired manner as will be readily understood. The sprocket gears are designed to be connected with suitable driving mechanism, which may be of any desired manner and which may be arranged for rotating the gears in reverse directions, but the blades and the gears may be arranged for rotation in the same direction and any other form of gearing may of 100 course be employed for transmitting motion to the longitudinal shafts. The rear portion of the longitudinal shaft 27 is provided at opposite sides with longitudinal guide openings 39 for the reception of the side shifting rods 25, which rotate with the outer shaft 105 and the bearing sleeve 35. The side bearing rods are connected at 110 their front ends to a rotary sliding sleeve 40 mounted on the inner longitudinal shaft and 115

120
125
130

provided with ribs 41, which fit in grooves 42 of a slideable sleeve 43. The slideable sleeve 43 is interlocked with the rotary sleeve 41 by the grooves and the ribs which 5 are of annular formation and which may be of any desired number, and the said slideable sleeve is held against rotary movement by a slide 44 mounted in a guide 45 of a base plate 46 suitably secured to the frame of 10 the machine, but it may of course be mounted in any other desired manner.

The central or inner longitudinal shifting rod 20 is provided at its front end with a sleeve 47 suitably secured to the said rod 20 and provided with exterior annular ribs 48 fitting in grooves 49 of a slideable sleeve 50 provided at the bottom with a slide 51 arranged in a suitable guide 52 of a base plate 53 suitably mounted on the supporting frame. The sleeve 47 is adapted to rotate within the slideable sleeve and it is interlocked with the latter, which is adapted, when moved longitudinally, to slide the rotary sleeve 47 and the shifting rod 20 backwardly and forwardly.

The slideable sleeves 43 and 50 are provided at their tops with ears or lugs 54 and 55, and the rear one of the lugs 54 and 55 is connected with the lower end of a lever 56, which is 20 fulcrumed at its upper end 57 on the frame and which depends from the top portion thereof. The lever 56 is connected at a point intermediate of its ends by a link 58 with an arm 59 of an actuating lever 60, and the 25 said lever 60, which is fulcrumed at 61, is provided with an arm 62 extending in the opposite direction from the arm 59 and connected by a link 63 with the lug or ear 55. The body portion of the lever depends from 30 the pivot 61 and constitutes a stem or main arm, which is connected by a rod 64 with an operating lever 65. The operating lever 65, which is fulcrumed at its lower end 66 on a suitable support 67, is provided with a 35 spring actuated dog or detent 68, which is connected with a latch lever 69 located adjacent to the handle portion of the operating lever 65. The spring actuated dog or 40 detent, which may be of any desired construction, is arranged to engage a toothed plate or segment 70 for locking the operating lever in its adjustment. Any suitable means, such as rock shaft connections or the like may be employed for connecting the 45 operating lever with the lever 60 in order that the operating device may be arranged in any convenient position. In practice the air propeller will be equipped with a suitable indicating device for indicating the 50 angle of the blades of the propellers.

What is claimed is:

1. A device of the class described including a central support, diametrically disposed blades arranged in pairs and having 55 reversely disposed crank elements, said

blades being mounted for rotary movement on their longitudinal axis, and a lever frame mounted on the central support and pivoted at a point intermediate of its ends and connected at opposite sides of the pivotal point with the reversely arranged crank element for simultaneously adjusting the propeller blades.

2. A device of the class described including a central support, diametrically disposed 70 blades arranged in pairs and mounted for rotary movement on their longitudinal axis, said blades being provided with crank elements the crank elements of each pair being oppositely arranged, a lever frame pivotally mounted intermediate of its ends on the central support and connected at opposite sides of the center with one set of the blades and provided at opposite sides with reversely arranged crank arms connected with the crank 80 elements of the other set of blades, and means for adjusting the lever frame.

3. A device of the class described including front and rear propellers having pivotally mounted propeller blades provided with 90 crank elements, front and rear lever frames mounted for rotary movement with the front and rear propellers and connected with the blades thereof, a central shaft connected with the rear propeller and having a longitudinal bore or opening, a central shifting rod mounted for reciprocation in the bore or opening of the longitudinal shaft and connected with the rear lever frame, an outer tubular shaft mounted on the inner 95 longitudinal shaft, side shifting rods carried by the outer longitudinal shaft and connected with the front lever frame, and means connected with the said rods for adjusting the lever frames.

4. A device of the class described including front and rear propellers having pivotally mounted propeller blades provided with 100 crank elements, front and rear lever frames mounted for rotary movement with the front and rear propellers and connected with the blades thereof, a central shaft connected with the rear propeller and having a longitudinal bore or opening, a central shifting rod mounted for reciprocation in the bore or 110 opening of the longitudinal shaft and connected with the rear lever frame, an outer tubular shaft mounted on the inner longitudinal shaft, side shifting rods carried by the outer longitudinal shaft and connected 115 with the front lever frame, an operating device, and means for connecting the operating device with the said rods for simultaneously adjusting the lever frames.

5. A device of the class described including front and rear propellers having pivotally mounted propeller blades provided with 120 crank elements, front and rear lever frames mounted for rotary movement with the front and rear propellers and connected with the 130

blades thereof, a central shaft connected with the rear propeller and having a longitudinal bore or opening, a central shifting rod mounted for reciprocation in the bore or opening of the longitudinal shaft and connected with the rear lever frame, an outer tubular shaft mounted on the inner longitudinal shaft, side shifting rods carried by the outer longitudinal shaft and connected with the front lever frame, rotary sleeves connected with the said rods and arranged at spaced points, slideable sleeves interlocked with the rotary sleeves, an actuating lever having arms connected with the sliding sleeves, and an operating lever connected with the actuating lever for simultaneously adjusting the lever frames.

6. A device of the class described including front and rear propellers having pivotally mounted propeller blades provided with crank elements, front and rear lever frames mounted for rotary movement with the front and rear propellers and connected with the blades thereof, a central shaft connected with the rear propeller and having a longitudinal bore or opening, a central shifting rod mounted for reciprocation in the bore or opening of the longitudinal shaft and connected with the rear lever frame, an outer tubular shaft mounted on the inner longitudinal shaft and connected with the front lever frame, sleeves rotating with the said inner and outer shafts and connected with the said rods and movable longitudinally, guides, slideable sleeves having slides arranged in the said guides, said slideable sleeves being interlocked with the rotary sleeves to permit rotary movement of the latter, and mechanism connected with the sliding sleeves for moving the same and the rotary sleeves longitudinally.

7. A device of the class described including front and rear propellers having pivotally mounted propeller blades provided with crank elements, front and rear lever frames mounted for rotary movement with the front and rear propellers and connected with the blades thereof, a central shaft connected with the rear propeller and having a longitudinal bore or opening, a central shifting rod mounted for reciprocation in the bore or opening of the longitudinal shaft and connected with the rear lever frame, an outer tubular shaft mounted on the inner longitudinal shaft and connected with the front lever frame, sleeves rotating with the said inner and outer shafts and connected with the said rods and movable longitudinally, guides, bearings receiving the said shafts and composed of bearing boxes and

inner rotary sleeves interlocked with the bearing boxes for holding the rotary sleeves against longitudinal movement, said rotary sleeves being fixed to the inner and outer shafts, and means for adjusting the said rods.

8. A device of the class described including front and rear propellers having pivotally mounted propeller blades provided with crank elements, front and rear lever frames mounted for rotary movement with the front and rear propellers and connected with the blades thereof, a central shaft connected with the rear propeller and having a longitudinal bore or opening, a central shifting rod mounted for reciprocation in the bore or opening of the longitudinal shaft and connected with the rear lever frame, an outer tubular shaft mounted on the inner longitudinal shaft and connected with the front lever frame, sleeves rotating with the said inner and outer shafts and connected with the said rods and movable longitudinally, guides, bearings receiving the said shafts and composed of bearing boxes and inner rotary sleeves interlocked with the bearing boxes for holding the rotary sleeves against longitudinal movement, said rotary sleeves being fixed to the inner and outer shafts, and the rear rotary sleeve being mounted on the outer shaft which is provided with guide openings to receive the side shifting rods, and means for adjusting the rods.

9. A device of the class described including front and rear propellers having pivotally mounted propeller blades provided with crank elements, front and rear lever frames mounted for rotary movement with the front and rear propellers and connected with the blades thereof, a central shaft connected with the rear propeller and having a longitudinal bore or opening, a central shifting rod mounted for reciprocation in the bore or opening of the longitudinal shaft and connected with the rear lever frame, an outer tubular shaft mounted on the inner longitudinal shaft and connected with the front lever frame, sleeves rotating with the said inner and outer shafts and connected with the said rods and movable longitudinally, guides, gears mounted on the shafts, and means for adjusting the shifting rods.

In testimony whereof I affix my signature in presence of two witnesses.

TONY FRANCISCO.
